ATTORNEYS.

UNITED STATES PATENT OFFICE

JOHN H. WIGGINS, OF TULSA, OKLAHOMA

FLOATING ROOF FOR LIQUID STORAGE TANKS

Application filed March 31, 1930. Serial No. 440,586.

This invention relates to floating roofs for liquid storage tanks of the type that comprise a substantially disk-shaped portion that covers the major portion of the liquid in the tank, and an upwardly-projecting, rigid, annular rim at the peripheral edge of said disk-shaped portion.

Heretofore the rims of such tank roofs have been formed from curved metal plates 13 reinforced and connected to the disk-shaped portion of the roof by curved angle irons connected to the web of the rim by welds extending around the entire circumference of the roof. The cost of curving the angles 15 and producing two complete circumferential welds constitutes an item of considerable importance in the cost of building the roof, and another objection to an annular rim formed from curved plates and curved angle irons 20 is that the radius on which the angles are bent has to be varied for roofs of different diameters, thus introducing a variable factor which is objectionable in the fabrication of tank roofs of different diameters.

25 One object of my present invention is to eliminate the curving operation heretofore required in constructing the annular rim of a floating roof for liquid storage tanks.

Another object is to reduce the weight of 20 a floating roof provided with an annular rim and also overcome the necessity of forming two complete circumferential welds in manufacturing the rim.

And still another object is to provide a 25 floating roof which is of such construction that straight flanged members of standard shape may be used to form the rims of roofs of various diameters.

Figure 1 is a fragmentary top plan view of 40 a floating roof for liquid storage tanks embodying my invention.

Figure 2 is a sectional view, taken on the line 2—2 of Figure 1, looking in the direction indicated by the arrows; and

45 Figure 3 is a perspective view, illustrating my preferred method of combining the U-shaped or channel-shaped members that constitute the rim of the roof.

50 In the drawing A designates a tank roof that comprises a substantially disk-shaped

portion that floats upon the liquid confined in the tank, and B designates as an entirety an upwardly-projecting rigid rim at the peripheral edge of the roof. The space between said rim and the side wall C of the tank 55 is closed by a structure commonly referred to as a "seal", which is herein illustrated as comprising shoe members D arranged in sliding engagement with the side wall of the tank and sustained by swinging hangers E on the 60 rim, and a flexible element F, usually formed from a substantially annular-shaped piece of gas-tight fabric having its outer edge attached by a gas-tight joint to the shoe members D and having its inner edge attached by 65 a gas-tight joint to the rim B of the roof. My present invention relates solely to the construction of the rim B of the roof, and therefore, it is immaterial what means is employed to close the space between said rim and the 70 side wall of the tank.

Instead of forming the rim of the roof from curved plates and curved angles, as has heretofore been the usual practice, I form the rim B of my improved roof from a plurality 75 of relatively short members of standard shape that can be produced easily and at a low cost by a simple straight flanging operation and joined together and attached to the roof without the necessity of forming complete circumferential welds. Said members 80 are formed from flat plates provided with integral, straight flanges, and said members are straight circumferentially of the roof and are arranged at the peripheral edge of the 85 roof in such a way as to produce a substantially polygonal-like structure that can be easily changed or modified to adapt it to circles of various diameters by simply varying the angle between any two sides of the 90 polygon. Said members are arranged in end-wise relation around the circumference of the roof, and they may either be disposed in abutting relation and connected together by butt straps, or they may be disposed in substantially telescopic relation.

In the preferred form of my invention, as herein illustrated, the rim B of the roof is made up of a plurality of relatively short channel-shaped members or U-shaped mem- 100

bers G, attached to the peripheral portion of the roof in such a way that they act collectively to form a vertically-disposed web of substantially annular form projecting upwardly from the top side of the roof and provided at its top and bottom edges with integral, laterally-projecting flanges that impart the required rigidity or stiffness to the rim and also enable the rim to be easily attached to the roof. Any suitable or preferred means may be used for connecting the members G together and for attaching said members to the roof, and the particular manner in which said members are combined or arranged relatively to each other is immaterial, so long as said members are disposed in substantially endwise relation and extend circumferentially around the peripheral edge of the portion of the roof that floats upon the liquid in the tank.

I prefer, however, to construct the rim from straight U-shaped members arranged horizontally, as shown in Figure 3, and proportioned so that one end of each member will telescope inside of an adjacent member, and the other end of said member will telescope outside of the member adjacent said enlarged end. When the members G are arranged in this manner the vertical webs 1 of said members will act collectively to form a substantially vertically-disposed annular rim, the top flanges 2 of said members will act collectively to form an integral, inwardly-projecting reinforcing flange at the top edge of said web, and the flanges 3 of said members will act collectively to form an inwardly-projecting, integral flange at the bottom edge of said web that is used to attach the rim to the peripheral edge of the portion A of the roof.

After the members G have been arranged in telescopic relation on the peripheral edge portion of the roof A, the overlapping parts at the ends of said members are joined together by welded joints and the bottom flanges 3 of said members are connected by welded joints to the roof on which said bottom flanges rest.

As previously stated, however, any other suitable or preferred means may be used to permanently join the members that constitute the rim and to attach said rim to the disk-shaped portion A of the roof.

The above described method of constructing the rim B reduces the cost of manufacturing the roof, as it overcomes the necessity of bending angle irons on an arc or radius, and it overcomes the necessity of forming two continuous ring-shaped welds that extend unbrokenly around the entire circumference of the roof. A rim B of the construction herein illustrated is rigid enough to successfully perform the function for which it is designed, but it is considerably lighter in weight than a rim provided at its top and

bottom edges with flanges formed by commercially rolled angles. As previously stated, the angular relationship of the members G can be easily changed, so as to produce a substantially circular rim of any desired diameter. This is a very desirable feature of my roof, as it overcomes the necessity of using special shapes for roofs of different diameters, thereby materially simplifying the operation of fabricating the roof. As the members G are of substantially U-shape or channel shape, they can be nested together when the parts of the roof are in transit from the place where said parts are cut or shaped to the point where the roof is to be installed, thus effecting a considerable saving in the space required to ship the parts of the roof.

Having thus described my invention, what I claim as new and desire to secure by Letters Patent is:

1. A floating roof for liquid storage tanks, provided at its peripheral edge with a flanged rim made up of a plurality of relatively short plates arranged in endwise relation and provided with integral, laterally-projecting flanges.

2. A floating roof for liquid storage tanks, provided at its peripheral edge with a vertically-disposed rim made up of a plurality of relatively short, channel-shaped members arranged horizontally in endwise relation.

3. A floating roof provided with a rim composed of a plurality of substantially channel-shaped members arranged horizontally with their end portions in overlapping relation and having their bottom flanges attached to the roof.

4. A roof for liquid storage tanks, comprising a substantially disk-shaped portion that floats upon the liquid in the tank, and an upwardly-projecting rim at the peripheral edge of said disk-shaped portion made up of horizontally-disposed channel-shaped members arranged in endwise relation with the ends of their webs and flanges lapped and permanently connected together, the bottom flanges of said members being attached to said disk-shaped portion.

JOHN H. WIGGINS.
